UNITED STATES PATENT OFFICE

121,901

DESIGN FOR A COMBINATION CAN OPENER AND HANDLE

Henry Weston Rice, East Boothbay, Maine

Application November 9, 1939, Serial No. 88,162

Term of patent 7 years

To all whom it may concern:

Be it known that I, Henry Weston Rice, a citizen of the United States, residing at East Boothbay, in the county of Lincoln and State of Maine, have invented a new, original, and ornamental Design for a Combination Can Opener and Handle, of which the following is a specification, reference being had to the accompanying drawing, forming part thereof.

Figure 1 of the drawing is a side view of a combination can opener and handle embodying my new design.

Figure 2 is an elevational view showing the inner side of the combination can opener and handle.

Figure 3 is a perspective view thereof.

Figure 4 is a view similar to Fig. 2 showing the outer side of the combination can opener and handle, and

Figure 5 is a top plan view thereof.

I claim:

The ornamental design for a combination can opener and handle, as shown.

HENRY WESTON RICE.
